UNITED STATES PATENT OFFICE

2,416,877

AERIAL MINE

Myron Penn Laughlin, St. Petersburg, Fla.

Application June 10, 1940, Serial No. 339,807

8 Claims. (Cl. 102—9)

1

This invention relates to aerial mines and to a method of laying and disposing the same.

Aerial mines of kite, balloon, and parachute type heretofore employed have involved moorings and the like to assure their being in position at a given time in a given spot, and hence have of necessity been made so large that they were not only expensive to prepare and maintain but were easily visible and avoided by the enemy with little trouble. Another difficulty with such devices has been that so large a proportion of their buoyancy was needed to support the mooring lines that but little remained to support any explosive elements. Further, the erratic gyrations of a balloon on a mooring in a breeze of any force often placed it far from its intended position when most needed to intercept enemy aircraft and the like.

It is the purpose of this present invention to provide a mine or grenade of such small size and cost that it may be made and used in large quantities, of a type and constructed of parts adapted to quantity production by peacetime production machinery so that it will be available in any quantity required, to provide means for so laying such mines that their position at a given time can be accurately known, and to provide means for automatically disposing of such mines after their period of effective use so that the danger from drifting and escaped mines may be eliminated.

The ultimate object of this invention is to provide means for accurately launching and controlling free-floating mines in such a fashion that the course of the free mines and of invading vessels will intercept and the point of such interception be accurately known.

The following description and the attached drawings will serve to disclose certain mechanism providing one embodiment of my invention and a preferred method of using the invention.

Fig. 1 is a view in partial cross-section of a preferred form of mine.

Figs. 2 and 3, also in partial cross-section, show parts of the firing mechanism of the mine of Fig. 1.

Fig. 4 is a fragmentary view of the trigger release mechanism.

Fig. 5 is a sectional view of the balloon inflating and deflating mechanism.

Fig. 6 is an elevation in partial section of the laying and setting mechanism.

Fig. 7 is a view taken in the direction of the arrows from line 7—7 of Fig. 6.

Fig. 8 is a view taken in the direction of the

2

arrows from line 8—8 of Fig. 6, and is in partial section.

Fig. 9 serves to show the mine storage and feeding rack used as a part of my invention.

Fig. 10 is a diagrammatic view of the aerial mines in operation.

Fig. 11 is a cross-sectional view of a preferred form of container for the mines and mine racks before use.

Fig. 12 is an elevation of part of the mechanism of Fig. 6.

Fig. 13 is a second view of the mechanism of Fig. 6 for the parts in a second position.

Fig. 14 is an end view of the mine rack of Figs.

15, 11, 12, and 13.

A type of aerial mine suited to the practice of my invention and forming a part thereof is illustrated in cross-section in Fig. 1, wherein 10s is the balloon shell of expansible type material such as rubber, rubberized cloth, or the like, provided with a neck or appendix 11, which forms the means of inflating the balloon, of supporting the explosive charge, detonator and firing mechanism, and of transporting all of this to the place of release. The method of manufacture of shell 10s, forms no part of this invention, and it may be made after any of the well known methods of manufacture, such as molding in a single piece or assembling in segments, and is preferably of spherical or pear-shaped form.

Within the appendix 11 is arranged a detonator mechanism 20, comprising a body 21, over which fits a shell 40. Body 21 is provided with an internal bore having an enlarged portion 22, opening into a reduced portion 23, which in turn opens into a bore 24, having an opening 25 in the side thereof, and opening in turn into a reduced bore 26, extending to the end of body 21 at the nipple 27, adjacent to which is provided a flange 28, whose purposes will be described.

The bore portion 22 serves to permit the introduction of a cap or cartridge 30 for which the bore portion 23 forms a chamber. Cap 30 is of a form well known to the art, and is exploded by the trigger and firing pin mechanism shown most clearly in Fig. 3.

In Fig. 3 it will be noted the shell 40 is provided with a thread 41, which in operation threads over thread 41a on the exterior of body 21.

Shell 40 is provided with a plug or bushing 42 in which slides firing pin 43, which terminates at its upper end in a loop 44, pivoting in hole 45 in the firing pin. Secured to firing pin 43 is a flange 46, against which bears springs 47, whose upper end attains a purchase on the closed end

of shell 40, which is bored to a sliding fit for firing pin 43, as may be seen in Fig. 3.

The trigger mechanism for firing pin 43 is provided in trigger 50, having a slot 51 engaging in a cutout 48 in the shell 40, so that the bearing portion 51a is interposed in the path of flange 46 and retains firing pin 43 in the raised position shown in Fig. 3, when trigger 50 is vertical as shown in Figs. 1 and 3.

Trigger 50 is provided in its upper end with an opening 53 in which a second ring or loop 52 pivots. Fig. 4 will serve to show the relationship of this firing mechanism when in a cocked position. Engaging the loop 44 and holding the relationship between the two loops and the cocked position of the trigger mechanism is a cord 60, having at its lower end a clip 62, as shown in Fig. 4.

Cord 60 may be a spring or the elastic cord illustrated which engages through a link 63, with a ring 65 secured by a suitable patch 66 to the wall of the balloon 10, opposite the appendix 11.

The mechanism thus far described will show that when the balloon shell 10s is inflated, cord 60 will place a tension upon the trigger mechanism and hold it cocked, and a slight consideration of the structure will show that any deflection of shell 10s beyond a predetermined amount will release the tension of cord 60 and permit the pressure of spring 47 to force flange 46 against the portion 51a of the trigger 50, and that trigger, pivoting about slot 51, will through ring 52 pull loop 44 down far enough so that the trigger 50 will be thrown out of the path of flange 46, and firing pin 43 will be driven down by spring 47 against cap 30, exploding the same, and discharging its flame and hot gas through the bore 24, and the opening 25, to detonate an explosive charge 70 arranged thereabout, as in Fig. 1.

Loop 44 and ring 52 are preferably secured together with fine wire 66 or the like when originally set and it will be understood that placing a strain upon cord 60 pulling up clip 62 breaks this wire.

The bore extension 26 of body 21 extends into and communicates with nipple 27 and serves to support the inflation valve mechanism shown in detail in Fig. 5. The inflation mechanism, Fig. 5, comprises a bushing 80, which journals a stem 81, having a valve disc 83 secured thereto, and normally seated on the upper end of bushing 80 by a spring 84.

The mechanism just described follows closely well known inflation mechanisms for rubber tires, and the like, and machinery for quantity production is in daily operation.

To provide an optional time element in the deflation of the balloon shell, a cap 85 for nipple 27 may be provided, cap 85 having escape vents 86, extending through its closed end and provided with an internal projection 87, which will engage the lower end of stem 81 to an extent, and with a pressure determine on the amount that cap 85 is screwed upon nipple 27. The purposes of this deflater mechanism will be described in more detail in connection with the operation of this device.

The following description will show that my invention contemplates a complete departure from the former haphazard methods of releasing aerial mines and contemplates an absolute accuracy and duplication in the mines themselves in their manufacture, in their individual operation, in their rate of travel, in the time of their release,

and in the time intervals between the release of individual units.

In the accomplishment of all of these objects, it is necessary that the firing mechanism or detonator, the explosive charge, and the balloon shell—in other words, all of the parts of the mine itself, be capable of accurate duplication, and this is provided by the quantity manufacturing methods already available to the parts involved.

It will be noted that all of the mechanical parts involved are such as to be readily produced by automatic machinery and that most of the parts so involved follow closely in form to those already employed in industry. It will be understood that inflation of balloon shell 20 cannot be entrusted to the former methods of manual operation if advantage is to be taken of the accurate duplication of parts already described.

Fig. 6 serves to show in partial cross-section a mechanism adapted to continue the absolute duplication and control essential to the best operation of my invention. In Fig. 6 the chuck 100 is of any of the forms and types well known to the tire inflation art wherein a valve mechanism is actuated by the insertion of a valve stem, and in this case by the insertion of nipple 27.

To avoid complication, drawings of the internal mechanism of chuck 100 have been dispensed with, but it will be understood that it is provided with a gas connection 101, to which is connected a suitable hose 102, communicating with the regulating valve 103, controlling the gas flow from such source as the gas cylinder 105.

Chuck 100 is preferably mounted on the body 112, sliding in the support 115 and pressed upward by spring 110, whose lower end bears upon a seat 114 and whose tension may be controlled by the adjusting screw 115a.

Body 115 is secured to cross-member 302 of a suitable supporting frame 301 as shown in Fig. 6. Cross-member 302 also serves to support the "weighing" and release mechanism which comprises a lever 150, having its end forked as indicated at 152f in Fig. 8.

Lever 150 journals upon the outer end of a suitable shaft 151, has upon its upper side a projection 154, and has therein a slot 155.

Secured to shaft 151 is a secondary lever 160, bearing upon its outer end a pin 162, which engages in slot 155 of lever 150.

Shaft 151 journals in a suitable bearing 161 and has secured to its inner end a lever 164, whose upper end is turned inward to engage hand nut 167, threading upon stem 168, whose lower end attaches to tension spring 169, anchored at 170 to the pedestal 172 of bearing 161. Pedestal 172 is secured to cross-member 302 already mentioned.

In lever 160 is also mounted a stop pin 162a, which projects from its lower surface and into whose path a timing mechanism 180 interposes a stop 182, as will be described.

Referring now particularly to Figs. 9, 11, 12, 13, and 14, it will be seen that the aerial mine of the form described in connection with Figs. 1, 2, 3, and 4, may be conveniently delivered to the place of operation in a sealed container or box 500, provided with the internal supports 501, which bear racks 510, having guides or slides 502 and 503 joined and separated by members 504 and 505, as specially shown in Figs. 13 and 14, in such fashion that the flange 28 rides between the guide rods 502 and is held thereby in regular arrangement as shown in the drawings.

Thus, the aerial mine complete may be shipped,

complete with explosives and detonator, but with the balloon shell deflated, as shown, and is ready to be fed unit by unit into the fork 152 of the inflating mechanism, as indicated in Figs. 12 and 13, it being understood that when lever 150 is in position 150a, as shown in Fig. 6, the end of this fork is in registry with the guide 502, and that only a slight side movement of the mine units is necessary to transfer from the shipping rack to the fork 152. Container 500 may be thus placed adjacent to the balloon discharging mechanism and the racks 510 picked up, each with its load of mine units, and positioned on frame 301, as indicated by the dotted lines 510d of Fig. 6. It is understood that such racks are omitted from Fig. 6 to avoid complication, and so that the source of inflation gas, might be shown.

It will also be seen that by this method nine units may be fed as rapidly as desired to the forks 152.

Flange 28 slides below fork 152, and appendix 11 projects thereabove when the arm 150 is in position 150a, as has been described. Arm 150 is supported in its raised position through the engagement of pin 162 to the upper end of slot 155, lever 160 being held in its uppermost position through the tension of spring 169 operated through lever 164 upon shaft 151, as indicated in Fig. 12.

It will be noted that hand nut 167 and threaded stem 168 provide means for regulating the tension of spring 169 and it will be seen that if the stem 168 be thrown to the right lever 164 will also be thrown to the right, and that the tension of spring 169 will now force lever 150 down, and pin 162 will engage the lower end of slot 155, as shown in Fig. 6, and force lever 150 and the mine unit carried thereby down so that nipple 27 will engage with and open chuck 100.

The tension of spring 169 is preferably greater than that of spring 110, supporting chuck 100, but it will be understood that both of these springs are of greater tension than that required to open chuck 100, and that as these two springs force nipple 27 and chuck 100 together gas flow from the cylinder 105 will begin and continue at the rate determined by the regulating valve 103, already described, the gas passing through hose 102 connection 101 to chuck 100, thence through nipple 27, the valve mechanism of Fig. 5, through bore 27, and opening 25 to the interior of the balloon shell 10s. It will be further understood that as this gas continues to flow the balloon shell 10s will be inflated and that the buoyancy of the whole will increase until not only the weight of the firing mechanism 20 and explosive 70 is borne, but the balloon commences to have a definite free lift over its total weight.

As this proceeds, cord 60 will be stretched, and in stretching will place a tension upon clip 62, breaking safety 66, so that the sole support for ring 52 and loop 48 becomes this same tension of cord 60, thus setting the mine and releasing its safety. The buoyancy of the balloon structure, as it increases, places an upward tension on arm 150, and this increases until the downward pressure of spring 169 is overcome and lever 164 is forced to the left, allowing arm 150 to rise and nipple 27 releases pressure upon chuck 100 (whose amount of vertical lift is controlled by stop pins 116 in the support 115, as shown in Fig. 8).

After sufficient upward movement to close chuck 100 and stop the gas flow, a further movement of arm 160 will proceed until stop pin 162a

encounters latch 182 of the timing mechanism 180.

The internal mechanism of timing mechanism 180 will be understood to follow a form of such devices well known to the art, and generally includes clock work or electrical mechanism individually controlled or connected through suitable electrical circuits with other mine mechanisms, after the fashion of those skilled in the art.

10 The inflation apparatus which has been described will be seen to provide means whereby a definite quantity of inflation gas, such as hydrogen, or the like, will be automatically introduced into each balloon unit as it is fed, and it will be seen that the tension of spring 169 will accurately control the free lift of the inflated balloon. Thus, each unit as it follows the preceding unit will have exactly identical free lift, and hence rate of ascension, when free in the air.

20 It will now be noted that timing mechanism 180, through its stop 182, provides means to release the accurately inflated balloon unit at an exactly predetermined time, and that when stop 182 is withdrawn from the path of stop pin 162a the tension of spring 169 will throw lever into position 150b and launch the balloon unit 10 through the wind protector and guide 300, surmounting the support frame 301. The instant after the balloon unit is launched the rack 510

25 provides means for instantly inserting a second unit 10 into fork 152 of lever 150, if stem 168 be thrown to the right; a further movement of stem 168 to the right will force lever 150 and the new balloon unit downward so that the stem 27 of 30 the new unit will contact and open chuck 100, and the new filling operation will immediately begin, it being understood that latch 182 is returned by the timing mechanism into the path of pin 162a, after the fashion of usual operation of 35 such mechanisms, and within the second or two necessary for the inflation gas to flow through chuck 100 and nipple 27 into the balloon shell.

40 Thus, a new balloon unit will have been fully inflated, chuck 100 will have again closed, and lever 150 will again return to position 150a, before the completion of the required time interval when timing mechanism 180 withdraws latch 182 to again release a balloon unit. This operation will, of course, be repeated over the specified total time of balloon release, as required.

45 Referring to Fig. 10 and to the preceding description of this specification, it will be understood that when a balloon unit for the known free lift is released its rate of ascension will be substantially constant, and that since this is true the altitude of each individual balloon unit at a given moment can be accurately predicted. The horizontal position of each balloon unit will, of course, be determined by the prevailing winds. Under a condition of no wind at any of the levels to which the balloon unit must pass, the ascent would, of course, be practically vertical. However, such conditions seldom, if ever, prevail.

50 It will be understood that Fig. 10 is for purposes of illustration only, and that in this illustration a uniform prevailing wind from lower left to upper right is assumed. Under actual operating conditions, however, different wind velocities and different wind directions will be encountered at various levels. This, however, will not affect the horizontal spacing of the balloon units, since release of a trial balloon and observation of its flight by theodolite, after the fashion well known in weather observations, will permit of determination of the line of flight of the following balloon

units, and once the horizontal path and rate is so determined it will be understood that the necessary dimensions can be added to that of altitude so that the position of a given balloon unit at a given instant may be accurately predicted. Thus, altitude and horizontal position being both known, the necessary position of the discharging units can be readily calculated, so as to interpose the balloon unit in the path of an attacking squadron of bombers, or the like, whose speed, altitude, and direction can be found by the sighting devices already in use for such purposes.

The method of discharge for individual balloon units, and the discharger which forms a part of the method, have been described. It is part of the purpose of this invention to duplicate such discharge in the necessary horizontal spacing as indicated in Fig. 10, so that the individual mines 10 will be discharged in substantially parallel lines of flight, and that while such lines of flight will hardly follow the ideal condition shown in Fig. 10, still, however, such lines of flight may be distorted by the winds at various levels, the mine units will maintain not only a vertical spacing, but also a fairly accurate horizontal spacing. It will be understood that such spacing may not necessarily be so close as to prevent the passage of an airplane between the individual shells 10, but that if desired entanglement wire such as 10w may be appended to each balloon unit as it is released, and that whether or no such entanglement wires are attached, the multiplicity of the balloon mines, their relatively small size, and their distribution over a large area, will form a mesh extremely difficult for a plane pilot, who must necessarily cut across and through the air currents, to avoid; that avoidance of such mines will be further complicated by their low visibility and by the air stream created through the plane propeller. The nightfall would, of course, further complicate the problem of avoiding such a mine field and add a mental strain factor deterrent to bombing raids.

The ability of balloon structures to rise not only through but above the possible altitudes for plane flight enables the mining officer to cover every possible plane altitude from zero to their "ceiling." The accuracy of spacing of the mines in the atmosphere permits the mining officer to provide channels or gaps in the mine spacing so that his own defending planes may fly through the mine field.

The removal of any mine from its active or primed condition is an essential factor if the defender's civilian population and countryside is to be protected. It will be seen that this invention provides means for so removing the primed mines in that the ascension of each balloon unit above a given predetermined altitude, depending upon the inflation ratio of the balloon shell, will cause the balloon shell to explode; such explosion, releasing the tension upon cord 60, will release the detonator and explode the mine.

The mine is similarly exploded on contact with the attacking planes or their propellers, and it will be seen that the balloon shell provides a fairly sensitive release mechanism in that in small sizes free balloons may be made of extremely thin fabric since they are called upon to sustain absolutely no mechanical strain beyond that of vertically bearing the load of the explosive and detonator which form the grenade.

It will be further understood that the grenade may be of small size, and the amount of ex-

plosive 76 small, since actual contact with any part of the necessarily fragile airplane shell and the explosion of a grenade there-against will effectually remove the plane from effective operation.

5 It will be further understood that explosive 76 may include any of the several thermite compositions used in incendiary bombs, together with a small explosive charge, and that detonation will 10 spread such incendiary charge over an attacking plane and over its appended bombs, exploding these while still in the air, in a fashion endangering the rest of the attacking squadron more than any object below.

15 Fig. 10 shows the dischargers as arranged on motor boats, but it will be understood that these may be equally well mounted in stationary positions or upon vehicles of any type, that the weight of such devices is not great, and that a single operator is sufficient for each such discharger.

20 The preferred modification of my invention which has been described serves to illustrate a method and means of accomplishing the same: It will be understood, however, that known equivalents within the arts involved may be substituted for any of the elements herein described, as an example of which may be cited the use of parachutes adapted to or forming a part of the balloon structure itself, so that the balloon on rising to 25 its fullest height may release the parachute device bearing the grenade mechanism on the downward flight, or bearing simply the entanglement wires, or the like. A further equivalent for the discharging mechanism would, of course, find embodiment in rotary devices and like feeders employing a multiplicity of arms and charging nozzles in simultaneous or consecutive operation.

I claim:

40 1. A balloon grenade, free lift controlled inflation means therefor and time responsive locking means for said inflation means operatively associated therewith to release said grenade at a predetermined instant.

2. In an apparatus for providing an aerial barrage, a balloon, and inflation means for the balloon including control means for the same operatively associated therewith and responsive to free lift of the balloon.

45 3. Apparatus for providing an aerial barrage of free balloons, said apparatus including a plurality of balloons each carrying an explosive charge with means to effect explosion thereof on contact of the balloon with an aeroplane, mechanism controlled by the buoyancy of the balloons 50 being inflated acting automatically to successively inflate the balloons to uniform buoyancy, and means operatively associated with said mechanism for releasing the balloons therefrom in timed sequence.

60 4. Apparatus for providing an aerial barrage of free balloons, said apparatus including a plurality of balloons each carrying an explosive charge with means to effect explosion thereof on contact of the balloon with an aeroplane, automatic mechanism for successively inflating the balloons to uniform buoyancy including a gas supply, a valve for the supply, a free lift weighing 65 mechanism operatively associated with said valve for governing the actuation of the same, and means operatively associated with said mechanism for releasing the balloons therefrom in timed sequence.

65 5. Apparatus for providing an aerial barrage of free balloons, said apparatus including a plurality of balloons each carrying an explosive 70 charge with means to effect explosion thereof on contact of the balloon with an aeroplane, automatic mechanism for successively inflating the balloons to uniform buoyancy including a gas supply, a valve for the supply, a free lift weighing mechanism operatively associated with said valve for governing the actuation of the same, and means operatively associated with said mechanism for releasing the balloons therefrom in timed sequence.

75 6. Apparatus for providing an aerial barrage of free balloons, said apparatus including a plurality of balloons each carrying an explosive

charge with means to effect explosion thereof on contact of the balloon with an aeroplane, automatic mechanism for successively inflating the balloons to uniform buoyancy including a gas supply, a valve for the supply, a free lift weighing mechanism operatively associated with said valve for governing the actuation of the same, and automatic means for releasing the balloons from said free lift weighing mechanism in timed sequence including timing means, a stop latch for the weighing mechanism, and a control responsive to the timing means and associated with the stop latch to withdraw the same and release the weighing mechanism.

6. In an aerial mine, in combination, a balloon unit including an envelope and firing mechanism including a firing pin released by destruction of the envelope, a separate explosive unit including a detonator, and assembly means for said units to ensure cooperation of the firing pin on one unit with the detonator on the other.

7. In an aerial mine, in combination, an explosive container unit having a percussion cap therein, a balloon unit comprising an envelope for buoyant gas and a mechanism section containing a firing pin for said percussion cap and means to release said pin upon a reduction in pressure of said gas in said envelope; and means to connect said units in operative relation whereby the firing pin on one unit may strike the cap on the other.

8. In a balloon inflating and releasing device, the combination with a balloon, of inflation instrumentalities therefor controlled by the buoyancy of the balloon, said instrumentalities including adjusting means for setting such control whereby an accurate preset lift of the balloon is obtained.
